US00D995640S

(12) **United States Design Patent** (10) **Patent No.:** **US D995,640 S**
(45) **Date of Patent:** **** Aug. 15, 2023**

(54) **GAME BOARD AND GAME PIECES**

(71) Applicant: **SMART, naamloze vennootschap**,
Kontich (BE)

(72) Inventors: **Leighton Meredith Rees**, Cirencester
(GB); **Raf Peeters**, Lier (BE)

(**) Term: **15 Years**

(21) Appl. No.: **35/514,580**

(22) Filed: **Jun. 14, 2022**

(80) **Hague Agreement Data**

Int. Filing Date: **Jun. 14, 2022**

Int. Reg. No.: **DM/221548**

Int. Reg. Date: **Jun. 14, 2022**

Int. Reg. Pub. Date: **Jul. 1, 2022**

(30) **Foreign Application Priority Data**

Dec. 15, 2021 (EM) 008799100-0006

(51) **LOC (14) Cl.** **21-01**

CLAIM

The ornamental design for a game board and game pieces, as shown and described.

DESCRIPTION

1. Game board and game pieces

Fig. 1.1 is a top perspective view of a game board and game pieces in accordance with the present design;

Fig. 1.2 is another top perspective view thereof;

Fig. 1.3 is a right side elevation view thereof;

Fig. 1.4 is a left side elevation view thereof;

Fig. 1.5 is a front elevation view thereof;

Fig. **1.6** is a back elevation view thereof;
Fig. **1.7** is a top plan view thereof; and
Fig. **1.8** is a bottom view thereof.
